(57) **CLAIM**

The ornamental design for a vacuum lancing device as shown and described.

DESCRIPTION

FIG. 1 is a perspective view of a vacuum lancing device, showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the vacuum lancing device in a use status;

FIG. 10 is a front elevational view of the vacuum lancing device without the silicone gasket; and,

FIG. 11 is an enlarged view of area 11 shown in FIG. 2. The evenly-spaced broken lines show portions of the vacuum lancing device that form no part of the claimed design; the dash-dot-dash broken lines represent enlarged sectional designations that form no part of the claim.
